DESIGN FOR A VENDING MACHINE CASING OR THE LIKE

John Tavis, New York, N. Y., assignor to Stewart
and McGuire, Incorporated, New York, N. Y.,
a corporation of New York

Application August 18, 1938, Serial No. 79,429

Term of patent 3½ years

To all whom it may concern:

Be it known that I, John Tavis, a citizen of the United States and a resident of the Borough and county of Queens, in the city and State of New York, have invented a new, original, and ornamental Design for a Vending Machine Casing or the like, of which the following is a specification, reference being had to the accompanying drawing, forming a part thereof.

In the drawing—

Figure 1 is a perspective view of a vending machine casing, showing my new design; and

Fig. 2 is a perspective view of the same in another position.

I claim:

The ornamental design for a vending machine casing or the like, as shown.

JOHN TAVIS.
